BRACKET AND HEADBOARD FOR VENETIAN BLINDS

James K. Heymer, Minneapolis, Minn.

Application October 14, 1937, Serial No. 168,927

10 Claims.

(Cl. 156—17)

My invention relates to Venetian blinds and particularly to brackets and headboards therefor.

It is highly desirable that the operating devices of Venetian blinds, particularly those used in residences, be concealed and that the concealing means and the supporting means for the blinds be of pleasing appearance. It is also desirable that the blinds be easily and quickly removable from and replaceable on the supports therefore without the use of tools, as for cleaning and other purposes, and yet normally be reliably retained on the supporting means.

An object of my invention is to provide Venetian blind-supporting brackets and headboards permitting easy and rapid removal of the headboards from the brackets and replacement of the headboards on the brackets.

Still another object is to provide such construction including means such as a removable facia board serving to simultaneously restrain the headboard from forward lateral movement thereof and conceal the headboard and blind operating mechanism.

A further object is to provide such a device of simple, light, compact, inexpensive, and easily installed construction.

These and other objects and advantages of the invention will more fully appear in the following description made in connection with the accompanying drawing, in which like reference characters refer to similar parts throughout the several views, and, in which:—

Fig. 1 is a partially broken away front view of an embodiment of my invention mounted on a window frame and supporting a Venetian blind;

Fig. 2 is a sectional view taken along the line 2—2 of Fig. 1 as indicated by the arrows and showing a facia board in normal and partially removed positions respectively in full and dotted lines; and

Fig. 3 is a sectional view taken along the lines 3—3 of Fig. 1 as indicated by the arrows.

Referring to the drawing an embodiment of my invention is shown associated with a window frame F and a Venetian blind "B". The Venetian blind includes the usual slats 4 supported by tapes 5 from a rotatively adjustable bar 6 in accordance with usual practice. One end of the bar 6 has an element such as the screw 7 extending outwardly therefrom and journalled in a bracket 8 which is carried by a headboard 9. The remaining end of the bar 6 is carried by a conventional form of device 10, also mounted on the headboard 9. The device 10 rotatively supports the associated end of the bar 6 and is ar-

ranged for control by means of a chain 10a whereby the bar 6 may be rotatively adjusted to dispose the Venetian blind slats 4 at various angles.

My invention is embodied in the headboard 9 and the brackets by means of which the headboard is supported.

My brackets each include a rectangular plate 11 adapted to be mounted on the window frame "F" so as to project forwardly therefrom in a vertical plane normal thereto. Each of the plates 11 has formed on the rear edge thereof a flange 12 adapted to be placed against and secured to the frame "F" as by means of screws 13. The flange 12 of each bracket of a pair thereof projects from the plate 11 toward the other bracket of the pair, that is, inwardly. The outer edge of each plate 11 is provided with a flange 14 also projecting inwardly toward the other bracket. The plates 11 are provided with apertures 11a in the rear marginal portion thereof for use in securing the plate 11 to window frames of such nature that the rear flanges 12 may not be secured to the frame.

Each of my brackets is provided with a horizontally extending member 15 of angular cross section secured to the inner side thereof between the respective forward and rearward flanges 14 and 12. The member 15 is shorter than the horizontal dimension of the plate 11 and one leg of the member 15 is secured to the plate 11 with the member 15 closely adjoining, at one end thereof, the rear flange 12. The inwardly projecting leg of the member 15 is arranged for use in supporting one end of the headboard 9. A medial portion of the inwardly projecting leg of the member 15 is cut away as at 15a to leave a space partially defined by ears 15b.

The upper side of the headboard 9 is provided with a longitudinally extending groove 9a and at one end of the headboard 9 a notch 9b is formed so as to leave projecting elements 9c adapted to at least partially register with the ears 15b so as to normally derive support therefrom. When it is desired to lower the end of the headboard 9 at which the elements 9c are situated, that end of the headboard 9 may be moved forwardly to shift the elements 9c out of registration with the ears 15b whereby the rearward one of the elements 9c may be lowered past the ears 15b through the space between the ears 15b and the forward one of the elements 9c may be lowered through the space situated forwardly of the forward one of the ears 15b. When the ele-

ments 8c have been lowered to a level below the lower edge of the plate 11, the headboard 9 may be moved longitudinally to the left (as viewed in Fig. 1) so as to move the right hand end of the headboard 9 out of engagement with the ears 15 of the right-hand supporting bracket. The headboard is then completely disengaged from both of the brackets.

Means is provided for normally maintaining the headboard 9 in its normal or rearmost position relative to the brackets. A facia board 16 is provided having a width substantially equal to the height of the plate 11 and having a length very nearly as great as the distance between the plates 11. The facia board 16 is placed at its respective ends immediately inwardly of the forward flanges 14 of the respective brackets. Small blocks 17 are secured to the inner side of the facia board 16 by suitable means so as to 20 occupy the space between the upper portion of the facia board 16 and the forward edge of the headboard 9 as shown in Figures 2 and 3. It should be apparent that the facia board 16 with the blocks 17 thereon will prevent forward movement of the headboard 9 from its normal position. The facia board 16 may be moved upwardly out of engagement with the flanges 14 when it is desired to release the headboard 9 for forward movement thereof out of normal position. To support the facia board 16 when the same is engaged with the flanges 14 a rearwardly projecting element 18 is formed on the lower edge of each of the forward flanges 14. The rearmost portion 18a of each of the elements 18 is turned 35 upwardly to restrain the lower marginal portion of the facia board 16 from rearward movement.

From the above it should be apparent that the headboard 9 is normally supported by the ears 15b of the above described brackets and the headboard 9 is restrained from movement out of at least partial registration with the ears 15b by the facia board 16 and blocks 17. The blocks 17 need only be used where the facia board 16 is thinner than the distance between the forward flanges 45 14 and the headboard 9.

The plates 11 of the supporting brackets and the facia board 16 serve not only as described above, but also function to conceal the headboard 9, the bar 6, the bracket 8 and the device 10. 50 The plates 11 of the brackets and the forward surface of the facia board 16 comprise smooth surfaces which may be colored or otherwise finished to present a pleasing appearance.

When a Venetian blind with my brackets, headboard and facia board is installed the brackets are first secured to the window frame in suitably spaced relation to each other. The headboard may next be sawed off at its right hand end to extend nearly through the entire distance between 60 the plates 11 of the respective brackets. The facia board may also be sawed off to a similar length. Since the ends of the headboard 9 and facia board 16 are concealed it is unnecessary to use particular accuracy in determining the length 65 to which they are cut.

It is apparent that I have invented a simple, compact, easily operated, and inexpensive combination of supporting brackets, headboard and facia board for Venetian blinds wherein the brackets and facia board not only serve for necessary mechanical functions but also serve as concealing means for certain relatively unsightly portions of a Venetian blind.

It will, of course, be understood that various 70 changes may be made in the form, details, propor-

tions and arrangements of the parts without departing from the scope of my invention.

What is claimed is:

1. Venetian blind construction comprising, a pair of brackets adapted to be mounted on a window frame and each including a member disposed in a vertical plane normal to said frame, one of said members having means for one end of a head board to rest upon, the second of said members having a horizontal series of spaced projections on the inner side thereof for the second end of a headboard to rest upon, and a headboard resting at its respective ends on said means and said projections, the second end of said board being cut away in portions to leave spaced projections normally approximately registering with and resting upon the projections of said second bracket whereby said second end of the headboard may be moved laterally to shift the projections thereof out of registration with the projections of said second bracket to enable downward movement of said second end relative to said second bracket. 15 20

2. The structure defined in claim 1 and releasable means for normally restraining the second end of said board against movement out of its normal position. 25

3. Venetian blind construction comprising, a pair of headboard-supporting brackets adapted to be mounted on a window frame and each including a plate disposed in a vertical plane normal to said frame and a horizontally extending flange mounted on said plate to project horizontally toward the remaining one of said brackets, and a headboard normally resting at its respective ends on the flanges of said respective brackets, one of said flanges and the end of said headboard associated therewith both being cut away in portions to leave respective normally approximately registering sets of spaced projections whereby said end of the headboard may be moved laterally to shift the projections thereon out of registration with the projections on said bracket to permit downward movement of said end past the projections on said bracket. 35 40 45

4. Venetian blind construction comprising, a pair of brackets adapted to be mounted on a window frame and each including a member disposed in a vertical plane normal to said frame, one of said members having means for one end of a headboard to rest upon, the second of said members having a horizontal series of spaced projections on the inner side thereof for the second end of a headboard to rest upon, a headboard resting at its respective ends on said means and said projections, the second end of said board being cut away in portions to leave spaced projections normally approximately registering with and resting upon the projections of said second bracket whereby said second end of the headboard may be moved laterally to shift the projections thereof out of registration with the projections of said second bracket to enable downward movement of said second end relative to said second bracket, means restraining said second end against lateral movement in one direction, and releasable means normally restraining said second end against lateral movement in the other direction. 55 60 65

5. Venetian blind construction comprising, a pair of brackets adapted to be mounted on a window frame and each including a member disposed in a vertical plane normal to said frame, one of said members having means for one end of a headboard to rest upon, the second of said members 70 75

having a horizontal series of spaced projections on the inner side thereof for the second end of a headboard to rest upon, a headboard resting at its respective ends on said means and said projections, the second end of said headboard being cut away in portions to leave spaced projections normally approximately registering with and resting upon the projections of said second bracket whereby said second end of the headboard 5 may be moved laterally to shift the projections thereof out of registration with the projections of said second bracket to enable downward movement of said second end relative to said second bracket, means on said brackets for restraining 10 said headboard against lateral movement out of normal position toward said frame, a facia board adapted to be placed in a position immediately forward of said headboard to restrain the same against lateral movement out of the normal position thereof in a direction away from said frame, and means on said brackets for releasably holding 15 said facia board in said position thereof.

6. Venetian blind construction comprising a pair of headboard-supporting brackets each including a plate attachable at its rear edge to a window frame to project forwardly and normally thereof in a vertical plane, a pair of ears projecting inwardly of each of said plates and spaced apart horizontally, and a headboard adapted to 20 rest at its respective ends on the ears of the respective brackets, one end of said headboard being formed into a pair of laterally spaced elements adapted to normally rest upon the respective ears of the corresponding one of said brackets, said end 25 of the headboard being movable forwardly to shift said elements out of registration with said ears to permit lowering of said elements past said ears.

7. The structure defined in claim 6 and releasable means for normally restraining said headboard against movement forwardly out of the normal position thereof.

8. Venetian blind construction comprising, a pair of headboard-supporting brackets adapted 45 to be mounted on the frame of a window, each of said brackets including, a plate projecting normal to said window frame in a vertical plane, a pair of ears carried by said plate medially of the height thereof and projecting horizontally 50 toward the other of said brackets from points respectively situated closely adjacent the rear edge of said plate and medially between the front and rear edges of said plate so as to leave a substantial space between said ears, a headboard adapted to rest at its respective ends on the ears of the respective brackets, one end of said headboard being formed into two elements normally resting upon the respective ears of the corresponding bracket and defining a notch between 55 said elements whereby said end of the headboard may be shifted forwardly to permit dropping of said elements through spaces disposed respectively forwardly and rearwardly of the forward one of said ears and subsequent longitudinal movement 60 of said headboard to withdraw the remaining end thereof from engagement with the remaining one of said brackets.

9. Venetian blind construction comprising, a pair of brackets adapted to be mounted on a window frame for supporting respective ends of the headboard of a Venetian blind, each of said brackets including, a flat plate adapted to be secured at one edge to said frame to project therefrom in a vertical plane normal thereto, a pair of horizontally inwardly projecting ears provided on the inner side of said plate a moderate distance below the upper limit thereof, one of said ears being situated closely adjacent the inner edge of said plate and the other being situated a moderate distance forwardly of said first ear to leave a space between said respective ears, a headboard adapted to normally rest at 10 its respective ends on the ears of the respective brackets and to be restrained from appreciable longitudinal movement by said plates, said headboard having a portion at one of its ends normally overlying the space between the ears of the 15 corresponding bracket removed to leave a notch at least as wide as the forwardmost one of said ears partially defined by elements normally resting upon the respective forward and rearward ears whereby said end of the headboard may be 20 shifted forwardly to align the rearward one of said elements with said space and position the forward one of said elements forwardly of said forward ear whereupon said end of the headboard may be lowered to a level below the corresponding bracket to enable longitudinal movement 25 of said headboard to shift the remaining end thereof off the ears of the remaining bracket.

10. Venetian blind construction comprising, a pair of headboard-supporting brackets adapted 30 to be mounted on the frame of a window, each of said brackets including, a plate projecting normal to said window frame in a vertical plane, a pair of ears carried by said plate medially of the height thereof and projecting horizontally 35 toward the other of said brackets from points respectively situated closely adjacent the rear edge of said plate and medially between the front and rear edges of said plate so as to leave a substantial space between said ears, a vertical 40 flange extending from the forward edge of each of said plates toward the other of said plates in forwardly spaced relation with the forwardmost of said ears, a headboard adapted to rest at its respective ends on the ears of the respective brackets, one end of said headboard being formed into two elements normally resting upon the respective ears of the corresponding bracket and defining a notch between said elements whereby said end of the headboard may be 45 shifted forwardly to permit dropping of said elements through spaces disposed respectively forwardly and rearwardly of the forward one of said ears and subsequent longitudinal movement of said headboard out of engagement with the remaining one of said brackets, and a facia board 50 normally disposed forwardly of said headboard and having ends normally disposed between said flanges and said headboard to restrain said headboard against forward movement from the normal position thereof.

JAMES K. HEYMER.
